UNITED STATES PATENT OFFICE.

FRED S. MORTON, OF WORCESTER, MASSACHUSETTS.

SHEET-METAL WHEEL OR ROLLER.

Application filed July 30, 1919. Serial No. 314,215.

To all whom it may concern:

Be it known that I, FRED S. MORTON, citizen of the United States, residing at Worcester, in the county of Worcester and State 5 of Massachusetts, have invented a new and useful Sheet-Metal Wheel or Roller, of which the following is a specification.

This invention relates to that class of wheels or rollers which are made of sheet 10 metal and usually provided with bearing balls at the center.

The principal objects of this invention are to provide a construction in which the web and rim can be formed of two pieces of 15 metal only, one half of the web being integral with the rim and the two halves secured together in any desired way; to provide a construction in which the usual cylindrical rim will not have to be made separately; to 20 provide a form which can be made by ordinary simple die stamping operations; and to provide a construction in which the rim will be double, the exterior being backed up by a rigid layer beneath, and provided with 25 integral means on one edge for holding the two halves firmly together.

Reference is to be had to the accompanying drawings in which

Fig. 1 is a side elevation of a wheel or 30 roller constructed in accordance with this invention; and

Fig. 2 is a central sectional view of the same.

Many designs of wheels both of sheet 35 metal and other material have been devised, but in most cases the web is formed of two pieces of metal and the rim is formed of a third piece fitting over them and consequently liable to become loose after use. 40 This invention is designed to do away with a considerable amount of die work required for the wheel and to reduce the number of pieces required for the main part of the work.

45 I have shown the invention as applied to a construction embodying a hub 10 provided with a circumferential groove 11 in which bearing balls 12 travel. The ball race is completed on the outside by two members 50 13 of hard metal of any ordinary construction. These parts 10, 11, 12 and 13 can be of any well known construction and do not constitute a part of this invention.

The web of the wheel is formed of two pieces of sheet metal 14 and 15. This preferably is soft metal which can be operated in dies. These two half webs are secured together by rivets 16 or in any other desired way and are provided with concave flanges 17 for supporting the ball race members 13. 55 60

The two main members 14 and 15 of the wheel or roller are turned outwardly at their outer ends to form two cylinders 18 and 19. These two cylinders are of the same thickness and the same diameter and constitute 65 inner treads. The cylinder 19 is cut off square at the edge 20 which constitutes the termination of this side of the roller. The cylinder 18 projects the same distance the other side. Then in addition to this a continuation of the edge, which at first is cylindrical and of the same diameter as the cylinder 18, is turned back over it to form the external rim or tread 21. This is twice as wide as the cylinder 18 so as to cover the 70 cylinder 19. It also has a projection 22 which at first is merely a straight end 23 as shown in dotted lines in Fig. 2.

The piece 15 is slipped into the cavity made inside the tread 21 up against the web 80 14 and secured in place and then the edge 23 is bent over all around against the flat edge of the cylinder 19 so as to hold the parts firmly together.

It will be seen that the tread 21 is in 85 contact with the rigidly supported cylinders 18 and 19 throughout nearly all of its internal circumference and that it is firmly fixed and locked to it at the edge besides being riveted through the web if that is 90 desired, but the riveting can be omitted in some classes of work on account of the positive manner in which the two parts are secured together at 23.

Any pressure applied to the exterior surface of the tread 21 that may be excessive is received by one of the cylinders 18 or 19 which backs up the tread. One of these is integral with the tread and the other practically fixed to it as if it were integral. 100 That is they receive the pressure and distribute it without danger of the parts becoming loosened under any pressure within that for which the wheel is designed, and furthermore on account of its rigid construction the wheel can be made to stand 105

the usual pressure without using as much metal as has been the case heretofore.

On account of having the rim or tread formed of a double thickness of metal in this way it is exceptionally strong even if the die work is not accurate enough to bring the parts into absolute contact as described above. In other words it will be a very strong construction even when made 10 with slight inaccuracies. The assembling of the parts is of the simplest character.

Although I have illustrated and described only one form of the invention I am aware of the fact that modifications can be made 15 therein by any person skilled in the art without departing from the scope of the invention as expressed in the claim. Therefore I do not wish to be limited to all the

details of construction herein shown and described, but what I do claim is:—

As an article of manufacture, a wheel comprising a web formed of two pieces of metal contacting with each other both being turned outwardly at their outer periphery to form two cylindrical inner treads 25 of exactly the same diameter and width, one of said inner treads being turned backwardly to form an integral cylindrical outer wearing tread engaging the exterior surface of the two inner treads throughout their 30 area and having a circular projection on its edge and rounded over to correspond with the shape of the offset edge.

In testimony whereof I have hereunto affixed my signature,

FRED S. MORTON.
